DESIGN FOR A BATHING SUIT

Mabel Sheldrick, New York, N. Y., assignor to Lee Knitwear Corp., New York, N. Y., a corporation of New York

Application May 15, 1945, Serial No. 119,556

Term of patent 7 years

(Cl. D3—17)

To all whom it may concern:

Be it known that I, Mabel Sheldrick, a citizen of the United States of America and resident of the city, county, and State of New York, have invented a new, original, and ornamental Design for a Bathing Suit, of which the following is a specification, reference being had to the accompanying drawing, forming a part thereof, in which

Fig. 1 is a front elevational view of a bathing suit embodying my design.

Fig. 2 is a side elevational view of the bathing suit shown in Fig. 1, and

Fig. 3 is a rear elevational view thereof.

I claim:

The ornamental design for a bathing suit, as shown.

MABEL SHELDRICK.
